EXHIBITION APPARATUS

Ebenezer W. W. Hoyt, Baltimore, Md.

Application November 12, 1937, Serial No. 174,239

1 Claim. (Cl. 272—13)

This invention is an arrangement by which articles intended for display may be readily exhibited to public inspection, while in fact concealed from the direct view and access of all observers.

One of the objects of the invention is to provide an exhibition chamber or enclosure for use by museums, stores and the like, containing a cabinet in which a valuable article may be concealed from direct public view, and yet the image thereof may be reflected to a position of observation, in such manner that the observer is optimally deceived into the belief that he is gazing directly at the article. A further object is to provide a chamber of the character mentioned which will be of simple and inexpensive construction, and equipped with adequate illumination, the parts thereof being so constructed and arranged as to produce a convincing illusive effect.

The invention will be hereinafter fully set forth and particularly pointed out in the claim.

In the accompanying drawing:

Figure 1 is a vertical sectional view on the line 1—1, Figure 3, illustrating an exhibition chamber constructed in accordance with the invention. Figure 2 is a horizontal sectional view on the line 2—2, Figure 1. Figure 3 is a front end elevation. Figure 4 is a horizontal sectional view illustrating a slight modification.

Referring to Figures 1, 2 and 3 of the drawing, 10 designates a normally closed chamber of approximately rectangular shape in plan view, the walls of which are of opaque and light absorptive material, so as to reduce all light reflection to a minimum. The front end wall is provided with an observation opening 11, through which an observer may view the article to be displayed.

Located within the chamber 10 is a cabinet 12, the walls of which are also opaque and non-reflective with respect to light. It is preferred to locate the cabinet 12 at the front end of chamber 10 with its top wall 13 located directly below the opening 11. The rear wall 14 of cabinet 12 is provided with an exposure portion 15, through which the image of the article A on display may be exposed to a mirror 16, which is mounted on the rear wall of the chamber 10. The portion 15 may be merely an unclosed opening, but is preferably formed of a glass panel, which should be clear glass, but may, if desired, be shaped in a well known manner to magnify or diminish the image of the article which is projected therethrough. The mirror 16 may be supported in any desired manner and may be of any desired con-

struction, it being preferably mounted in guides 17, so that its height may be adjusted with respect to the article A and the opening 11, in such manner as to produce the best delineation of said article at said opening. The mirror may be colored if so desired.

Secured to the rear edge of the top wall 13 of cabinet 12 is an elongated lamp casing 18 in which is located an elongated electric lamp 19 of well known construction and mounted in such manner that the light rays may be projected through an opening 20 in the side of said casing 18 and directly onto any object A so as to clearly illuminate the same and irrespective of the size thereof. Located in the upper portion of the chamber 10 is an opaque ceiling 21 which is inclined from a position directly above the opening 11 to a position adjacent the upper end of the mirror 16, and also arranged to lie approximately parallel with the general line of reflection of the image from the mirror to the opening, so as to reduce the possibility of dispersion of light entering said opening.

From the foregoing, it will be readily seen that the article A may be placed within the cabinet 12 so that it would be absolutely invisible as well as inaccessible to persons on the outside of the cabinet, except for the image thereof which is reflected by the mirror. The illumination of the lamp 19 is such that a well defined image of the article A is directly projected to the mirror 16 and from the mirror directly to the opening 11, so that the observer upon looking into the chamber 10 through the said opening 11 will be under the optical illusion that he is directly viewing the article A. The arrangement of the lighting with respect to the object A, the mirror 16 and the opening 11 is such that the illusion will be exceedingly difficult to discover.

In Figure 4 is shown a slight modification in which the chamber is arranged for the observation of the article on display from a plurality of different positions. In this form, the front end is provided with a plurality of angularly arranged front walls 11^a, each with an opening 11^b therein. In the same manner the rear wall is provided with correspondingly arranged angular portions 16^a, each of which is provided with a mirror 16^b. The cabinet 12^a is also provided with a lamp casing 18^a so positioned as to illuminate the object on display which is exposed to all of said mirrors in the manner described with respect to Figure 1, and is reflected by the respective mirrors to the respective openings 11^b. In Figure 4, arrangement is made for the article to be simultaneously

observed by three different persons, but it is obvious that the number may be varied without departing from the spirit of the invention, by merely changing the number of mirrors and the respective observation and exposure openings related thereto.

The advantages of the invention will be readily understood by those skilled in the art to which it belongs. For instance, it is not unusual for exhibitors to hesitate in granting permission for the exhibition of valuable museum pieces, because of the danger of theft and vandalism. By the arrangement herein described and claimed, it is possible to completely protect the article from physical access by any person on the outside of the exhibition chamber and yet the same may be satisfactorily displayed in such a manner that the average person will not realize that he is not directly viewing the article on display. A further advantage is that the arrangement is exceedingly simple and inexpensive in construction, and may be readily adapted for the display of any kind of an article which it may be considered desirable to place on exhibition. It is to be understood that the mirrors are diagrammatically shown on the drawing without intent to limit as to type or number which may be required to reflect the image of the article on display to the desired observation position in ways well understood in the art.

Having thus explained the nature of the invention and described an operative manner of constructing and using the same, although without attempting to set forth all of the forms in which it may be made, or all of the forms of its use, what is claimed is:

An exhibition apparatus comprising a closed chamber having a plurality of angularly disposed walls at one end thereof, each wall having an observation opening therein, a plurality of angularly disposed mirrors located within said chamber adjacent an oppositely disposed angular end wall of said chamber, there being one mirror positioned opposite to each of said observation openings, a display cabinet for the article to be displayed, said cabinet being located within the chamber adjacent to the first mentioned end wall but below the plane of the observation opening, the rear wall of said cabinet having an exposure opening through which said article is simultaneously exposed to all of said mirrors, and a source of light located outside of the cabinet at a position between the mirrors and the article and so placed as to illuminate the latter through the exposure opening, the mirrors and said observation openings being so positioned with respect to the observation opening that the article is simultaneously reflected through a single exposure opening to all of the observation openings.
